ARTIFICIAL FISH BAIT

Carl R. Cordell, Jr., Hot Springs, Ark., assignor to James Heddon's Sons, Dowagiac, Mich., a corporation of Michigan

Filed Dec. 14, 1964, Ser. No. 83,025

Term of patent 14 years

(Cl. D31—4)

FIGURE 1 is a side elevational view of an artificial fish bait embodying my new design;

FIGURE 2 is a side elevation thereof, with portions of the broken line structure omitted for convenience of illustration;

FIGURE 3 is a top view thereof;

FIGURE 4 is a bottom view thereof;

FIGURE 5 is a front elevational view thereof; and

FIGURE 6 is a rear elevational view thereof.

The dominant features of my design reside in the portions shown in solid lines.

I claim:

The ornamental design for an artificial fish bait, as shown and described.
